Inventor

G. P. Jordan.

UNITED STATES PATENT OFFICE.

G. P. JORDAN, OF BURLINGTON, IOWA.

SEPARATOR FOR SMUT-MACHINES.

Specification of Letters Patent No. 24,126, dated May 24, 1859.

To all whom it may concern:

Be it known that I, G. P. JORDAN, of Burlington, in the county of Des Moines and State of Iowa, have invented a new and Improved Separator and Smut-Machine; and I do hereby declare that the following is a full, clear, and exact description of the same, reference being had to the annexed drawings, making a part of this specification, in which—

Figure 1, is a vertical central section of my invention, taken in the line x, x , Fig. 2. Fig. 2, is a horizontal section of the same, taken in the line y, y , Fig. 1.

Similar letters of reference indicate corresponding parts in the two figures.

This invention consists in a peculiar arrangement and combination of parts, substantially as hereinafter fully shown and described, whereby the desired work, to wit, the separating of smut and other impurities or foreign substances from grain is effected by a very simple machine and in a perfect manner.

To enable those skilled in the art to fully understand and construct my invention, I will proceed to describe its construction and operation.

A, represents the frame of the machine, which may be constructed in any proper manner to support the working parts. In the upper part of the frame A, a horizontal box B, is placed. This box has two parallel partitions a, a , placed in it, said partitions forming three chambers, b, b, c , two of which, b, b , communicate directly with a chamber C, the upper end of which communicates with a blast spout D, of siphon form, as shown clearly in Fig. 1. The lower end of the blast spout D, is made of sinuous form, as is also shown clearly at d, d , in Fig. 1.

Below the box B, a fan box E, is placed. F, is the fan, of usual construction, and placed on a shaft G, the lower end of which is stepped in the lower part of the frame A, as shown at e. The fan box E, communicates with the central chamber c , of the box B, as shown at f, Fig. 1. The outer ends of the partitions a, a , are connected by a curved screen g, and all three chambers b, b, c , communicate with a spout H, having a flap h, at its lower end.

On the top of the box B, a screen I, is placed. This screen is formed of three horizontal wheels J, which are attached to the

same shaft G, as the fan E. These wheels have radial inclined and corrugated arms i, and are provided at their peripheries with vertical plates or segments j, the outer surfaces of which are fluted or corrugated vertically, as shown clearly in Fig. 1. The plates or segments j, extend from one wheel to the other. The wheels J, are encompassed by a perforated cylinder K, and the cylinder K, is encompassed by a tight cylinder L, a space R, being allowed between the two cylinders which space communicates with the chambers b, b , of the box B, by means of openings l, which are shown in Fig. 2. The inner side of the perforated cylinder K, has oblique-faced corrugated plates m, attached to it. These plates m, extend nearly the whole height of the cylinder K. The cylinder K, is covered by a plate n, the under side of which is provided with radial inclined plates having corrugated faces, and in the plate n, two oblong openings o, p, are made, one opening o, being provided with a flap q. The lower part of the scourer communicates by means of an opening r, covered by a screen or sieve s, with a spout t, which communicates with the external air and the lower part of the scourer also communicates with a spout t¹, which leads into the spout D, just above its sinuous lower part d.

On the box B, a frame or stand M, is placed. This frame or stand has a shoe N, fitted in its upper end, said shoe having a shake motion given it in any proper way. In the shoe N, two screens u, v, are placed. The upper screen u, being coarse and allowing the wheat or grain to pass through it, and the lower screen being fine and allowing only finer particles than the grain to pass through it. The bottom of the shoe N, communicates with a spout O, and the fine screen v, has a spout w, attached, as shown clearly in Fig. 1.

The upper end of the spout D, communicates with the interior of the scourer I, and a partition plate a¹, is placed in this end of the spout, one portion of the spout communicating with the opening p, and the other part with the opening o, the latter part having a screen b¹, fitted in it.

In each partition a, a, of the box B, a valve c¹, is placed.

The operation of the machine is as follows. The wheat to be cleaned passes on the screen w, and is allowed to pass through

it, the coarse foreign substances falling off the depressed end of the screen. The grain, deprived of coarse foreign substances, falls on the finer screen *v*, through which it can- 5 not pass.

The finer foreign substances pass through screen *v*, and are conveyed by the spout *O*, into the spout *H*, in which there is a blast generated by fan *F*, the light foreign sub- 10 stances, such as dust, etc., being drawn up into the fan box *E*, and ejected therefrom, while the heavier fine substances, such as fine seeds, cockle, etc., drop through flap *h*. The wheat or other grain passes into the 15 nearest part of the spout *D*, and through the opening *o*, into the scourer *I*. The grain is subjected to its first blast as it passes the screen *b*¹, and additional light foreign sub- stances are taken therefrom. The grain 20 then passes through the scourer and is subjected to a scouring action by the arms *i*, and plates *j*, of the wheels *J*, in combination with the stationary plates *m*, attached to the perforated cylinder *K*. The plates *m*, 25 as the grain is thrown against them by the wheels *J*, serving to deflect the grain back again and thereby subjecting it to a perfect scouring action. The grain while being scoured is subjected to a blast that carries 30 the loosened smut up through the opening *p*, into the chamber *C*, and into the chambers *b*, *b*, and through the valves *c*¹, into the fan box *E*; the valves *c*¹, however if it is desired to retain all the offal, are closed, the 35 blast passing entirely through the screen *g*. The grain leaves the scourer *I*, through the

spout *t*¹, and passes into the lower sinuous portion of the spout *D*, where it is again subjected to a blast in a very effective manner, the grain being deflected from one side 40 of the spout to the other, see red arrows, Fig. 1. The clean grain falling from the end of the spout *D*. All smut or dust that passes through the perforated cylinder *K*, is drawn by a blast through the openings *l*, 45 into the chambers *b*, *b*.

From the above description of parts it will be seen that the smut is taken upward from the grain as soon as it is separated from it, the flap *g*, preventing any smut 50 passing through the opening *o*. The machine is very compact, has been practically tested and operates in the most efficient manner.

Having thus described my invention what 55 I claim as new and desire to secure by Letters Patent, is—

1. The combination and arrangement of the scourer *I*, with the spout *D*, chamber *C*, and box *B*, provided with the blast chambers *b*, *b*, spout *H*, fan *F*, and screens *u*, *v*, substantially as and for the purpose set forth. 60
2. The employment or use of the valves *c*¹, placed in the partition plates *a*, *a*, when used in combination with the fan *F*, chamber *C*, spout *D*, and scourer *I*, and arranged relatively therewith as and for the purpose set forth. 65

G. P. JORDAN.
